UNITED STATES PATENT OFFICE.

WILLIAM S. WILSON, OF LOS ANGELES, CALIFORNIA.

NOVELTY SETTING.

Application filed December 12, 1923. Serial No. 680,178.

To all whom it may concern:

Be it known that I, WILLIAM S. WILSON, a citizen of the United States, residing at Los Angeles, in the county of Los Angeles and State of California, have invented certain new and useful Improvements in Novelty Settings, of which the following is a specification.

My invention relates to improvements in novelty settings for use on rings, jewelry, or other articles of personal use, such as canes, umbrellas, pocket books, etc.

I am aware that hitherto settings have been constructed adapted on the manipulation thereof to display insignia, but so far as I am aware I am the first to construct a setting adapted of its own inherent structure to display the insignia when desired. I am aware that settings have been constructed adapted to change their appearance when moved, but I believe I am the first to provide a setting employing the inertia of one member thereof to display and hide the insignia as desired. To these ends I provide a box setting having an opaque cover having a transverse transparent opening and a member displaying the insignia on its upper surface, slideable in said box adapted on the manipulation thereof to slide the insignia in and out of alignment with the transverse transparent opening.

One object of my invention therefore is to provide a novelty setting adapted to display insignia at the wearer's will.

Another object of my invention is to provide a novelty setting of simple construction adapted to function on the movement of the setting alone, without the necessity of applying an outside manipulative force, thereby dispensing with the members necessary for the outside force to work upon, such as pivots, etc.

A further object of my invention therefore is to provide a setting which if used in a ring may be manipulated by the movement of one hand alone.

These and such other objects of my invention as may hereinafter appear will be best understood from a description of the embodiments thereof shown in the accompanying drawings for use on an ordinary finger ring.

In the drawings, Fig. 1 is a perspective view of a finger and a ring employing my invention, with the finger in horizontal position.

Fig. 2 is a perspective view similar to Fig. 1 showing the hitherto concealed insignia displayed.

Fig. 3 is a cross sectional view of a ring embodying my invention.

Fig. 4 is a top view of a ring employing my invention with the cover and opaque portions thereof removed.

Fig. 5 is a perspective view of the slidable member.

Fig. 6 is a cross sectional view of a modified form of my invention.

In the drawings, wherein like characters of reference indicate like parts throughout, 70 10 represents a typical ring finger to which is secured as usual the band annulus 11 having my improved box setting 12 attached thereto, to be displayed as normally. I employ the terms "inner" and "outer" with reference to the base 15 of the setting, and the words "upper" and "lower" with reference to the position of the setting when the finger 10 is held in lowered position. The setting 12 includes the box portion 14 which may be conveniently stamped out of one piece of stock having one half the band portion attached thereto at each side thereof (not shown). The side walls 16 project outwardly from the base 15, and are constructed to have a shoulder 17 projecting centrally therefrom around the interior of the setting. It is obvious that the box portion 14 may be of any suitable shape and is not limited to the rectangular shape shown. The simplified modification illustrated in Fig. 6 shows the essential parts of the setting. As constructed, a suitable space 18 is left between the base 15 and shoulder 17. Suitably mounted on the shoulder 17 is the cover portion 20. The upper edges of the sides 16 are suitably beveled or burnished over as at 21, to secure the cover portion 20 thereto. The cover portion 20 is preferably made in one piece and of transparent material. Opaque strips 23^a and 24^a, preferably of metal, are placed underneath the cover 20, and spaced apart, so as to define between them a central opening. There is thus formed, as shown in Fig. 1, opaque portions 23 and 24 and a central opening 25 covered by the transparent cover 20. The opaque portions 23 and 24 could, of course, be formed in other ways than by the use of metallic strips. Loosely contained within the space, runway or pocket 18, is the slidable member 27. Said member 27 preferably comprises a plate

preferably made of metal, having the insignia 28 displayed in the outer surface thereof.

The embodiment shown in Figs. 1 to 4 comprises the preferred form, and is adapted to show alternately different insignia, depending on whether or not the plate 27 is exposed through the transparent portion 25. One insignia 28, a crescent as shown, is displayed as usual on the upper surface of the plate 27 as in the embodiment aforescribed, whereas the other insignia 30, a star as shown, is displayed through the transparent portion 25 on either the base 15 itself or on the member 31, preferably a metallic plate, suitably secured to the base. The member 31 is preferably a force fit on the base 15 within the box 14. This member is employed for it is usually easier to print the insignia on this member than directly on the base. The member 27 slides in the pocket 18 as usual.

The setting may be assembled as follows: The member 31 is inserted on the base 15 within the box portion 14, the opaque members 23^a and 24^a inserted in their respective ends of the box portion 14 over the shoulder 17 so as to leave the transparent transverse portion 25 therein, over the insignia bearing portion 28 of the slidable plate when moved in position to display said insignia, the cover portion 20 inserted on top, and the outer edges of the side walls 16 bezeled or burnished as at 21 to secure the cover 20 to the box portion 14.

The operation of my invention is obvious from the above description. Fig. 1 illustrates the finger in substantially horizontal position displaying the insignia 30 on the plate member 31 through the portion 25, and having the member 27 completely hidden in the upper end 35 of the pocket 18 (Fig. 3). Though I have shown for purposes of illustration the finger in horizontal position, it is obvious that the member 27 will be retained by friction between the plate 31 and strip 24^a, Fig. 3, or between base 15 and strip 24^a, Fig. 6, during all normal movements of the hand. When it is desired to display the insignia 28 on the slidable member 27, which may be the insignia of some secret organization, the hand is sharply jerked down, leaving the finger 10 in slanting position as shown in Fig. 2. When the downward movement of the finger is arrested, the box portion 14 will stop with the hand, but the inertia of the slidable member 27 will cause it to overcome the friction and slide forward into the then lowered lower end 36 of the setting 12, until it abuts the lower end thus exposing the insignia 28 through the transparent portion 25. The effect of gravity on the slide 27 of course aids this downward movement of the slide. Then during normal movements of

the hand, the insignia 28 will be retained by friction in the lower end 36 of the pocket 18 and be thus exposed to view. To withdraw the member 27 with its insignia 28 once more to the upper end 35, the hand 70 and finger are sharply raised upwards to the horizontal position shown in Fig. 1, or otherwise jerked upward, the inertia of the disk 27 overcoming the frictional resistance and causing it to slide once more to the 75 upper end 35 of the pocket 18 at the end of the movement, thus again exposing the insignia 30 to view, as illustrated. In the embodiment shown in Fig. 6 the portion exposed to the portion 25 may be blank, and 80 the insignia 28 only exposed when the member 27 is lowered underneath the portion 25.

Though I have shown a crescent and a star as the insignia, it is obvious that any suitable insignia may be displayed in either 85 set or only one set as shown in Fig. 6. My invention is peculiarly adapted to display the insignia of secret organizations. I employ the word insignia to include letters, words, marks, numbers, figures, characters 90 or any conceivable kind of a distinguishing representation.

The slide 27 has been described as held between cover and base by slight friction. This friction may be lessened by making 95 the slide slightly thinner or the space 18 slightly deeper, whereby the slide is more loosely and freely movable in this space so that the effect of gravity alone is sufficient to move the slide, when the ring is turned 100 upside down.

It is understood that my invention is not limited to the specific embodiments shown, and that various deviations may be made therefrom without departing from the spirit 105 and scope of the appended claims.

What I claim as new and desire to secure as Letters Patent is:

1. A finger ring comprising a base member, a cover member spaced slightly away from said base member, an aperture in the cover, and a slide movable back and forth in the space between the base and cover so as to be visible through the aperture or so as to be concealed below the cover, the movement 110 of the slide being effected solely by movement of the ring and without the application of an outside manual force to the slide.

2. A finger ring comprising a base member, a cover member spaced slightly away from said base member, an aperture in the cover, and a slide movable back and forth in the space between the base and cover so as to be visible through the aperture or so as to be concealed below the cover, the movement 120 of the slide being effected solely by gravity when the ring is turned upside down.

3. A disappearing emblem ring comprising 125 a base member, a cover spaced from the

base member and provided with an aperture, a slide member movable back and forth so as to be visible through the aperture, or so as to be concealed below the cover, one of 5 said members bearing an emblem that may be concealed or displayed, upon movement of the slide member, the movement of the slide member being effected by movement of the ring, without the application of an outside 10 manual force to the slide member.

4. A disappearing emblem ring comprising a base member, a cover spaced from the

base member and provided with an aperture, a slide member movable back and forth so as to be visible through the aperture, or so 15 as to be concealed below the cover, one of said members bearing an emblem that may be concealed or displayed, upon movement of the slide member, the movement of the slide member being effected by gravity 20 when the ring is turned over, without the application of an outside manipulative force.

In testimony whereof I affix my signature.

WILLIAM S. WILSON.
